UNITED STATES PATENT OFFICE.

LEROY VORHIES, OF DENVER, COLORADO.

HYDRAULIC DREDGING MECHANISM.

Application filed April 28, 1927. Serial No. 187,361.

My invention relates to hydraulic dredges for use in rivers, creeks and washes for the recovery of gold and other minerals.

My objects are to provide a dredging mechanism including a slidably mounted swinging frame carrying a ground engaging member; to provide means for lowering and lifting said frame; to mount pumps in said frame so that said pumps will work under water and thereby require no priming; to dispose said pumps so that the center of gravity of the dredging mechanism will be low; to provide means to dislodge sand from crevices while adjacent to the ground engaging member and to provide means to wash sand from between the impeller of the sand pump and the bottom of the pump. Other objects will appear as the description progresses.

In Patent Number 1,597,580 and in a co-pending application filed September 11, 1926, Serial Number 134,869, hydraulic dredges are described provided with swinging beams carrying ground engaging members working in conjunction with centrifugal pumps mounted on the boats. In the present invention I use a swinging frame carrying a ground engaging member provided with two water channels in addition to a sand channel, and mount the pump directly on the ground engaging member so as to keep the pump under water and also add weight to the ground engaging member to keep it in working engagement with the ground. A water pump is provided to cooperate with the water channels in the ground engaging member to dislodge sand from crevices and to wash sand from between the impeller and the bottom of the sand pump so as to reduce the abrasive effect the sand would otherwise have on the pump. This disposition of the pumps locates the center of gravity considerably lower than in the inventions above mentioned.

Figure 1 represents a side elevation of a boat with my dredging mechanism mounted thereon; Fig. 2, a fragmentary side elevation of the lower portion of the dredging mechanism, drawn to an enlarged scale; Fig. 3, a plan view of Fig. 2; Fig. 4 an end elevation of Fig. 2; Fig. 5, a sectional plan view of Fig. 4, on the line A—A; Fig. 6, a plan view of the ground engaging member; Fig. 7, a vertical cross section of Fig. 6, on the line B—B; Fig. 8, an enlarged fragmentary vertical cross section elevation through the center of the pumps; Fig. 9, a sectional plan view of the sand pumps, on the line C—C in Fig. 8; Fig.

10, a sectional plan view of the water pump on the line D—D in Fig. 8; Fig. 11, a fragmentary side elevation showing the lifting means; Fig. 12, a sectional plan view of Fig. 11, on the line E—E; Fig. 13, a side elevation of Fig. 11, beam 4 being partly broken away to show the drum 70 and frictional wheel 60; Fig. 14, a fragmentary elevation showing different positions of the friction disc 59; Fig. 15, a view of the under side of the impeller of the sand pump to show the grooves 81, and Fig. 16, a sectional view of Fig. 15, on the line G—G.

Although I show the preferred embodiment of my invention, I do not thereby limit myself to the precise form shown, but wish it understood that within the scope of what hereinafter is claimed, various changes in the details of construction may be made without departing from the spirit of the invention.

A boat 1 is provided with a frame work like that shown in my copending application and comprises vertical standards 16 mounted on longitudinally disposed beams 16^a and braced by beams 18, said standards supporting a transversely disposed beam 17 carrying journals 20.

An open sleeve 2 is rotatably mounted on a journal 20. A frame, comprising beams 3—4 connected by cross beams 5, 6 and 7, is slidably mounted in sleeve 2 by disposing beam 3 within said sleeve.

A hollow ground engaging member A is secured to the lower end of said frame by bolts 86. This member A is provided with a sand channel 8 and water channels 9—10. Water channel 9 is provided with an intake port 11 and a tapering discharge 12 and water channel 10 has an intake port 13 and a discharge 14. Both water channels are open above.

A centrifugal sand pump B is mounted on the ground engaging member A and secured to the beams 3—4 by bolts 84. The sand pump B is provided with a sand intake 19 in communication with sand channel 8 of the ground engaging member, two sand outlets 20—21, two water intake ports 22—23 in communication with water channels 9 and 10, respectively, in member A, and two removable linings 24—25. A sand conduit 26 is connected to outlet 20 and a sand conduit 27, connected to outlet 21. These two sand conduits are connected to a main sand conduit 28 which communicates with a riffle box 31 via a flexible conduit 29 and conduit 30.

- A centrifugal water pump C, having an intake 32 and two outlets 33—34, is disposed above sand pump B and secured to beams 3—4 by bolts 85. A pipe 35 extends downward from outlet 33 and connects with intake port 11 of water channel 9. A pipe 36 extends downward from outlet 34 and connects with intake port 13 of water chamber 10.
- 10 An electric motor 37 is mounted between cross beams 5 and 6, the drive shaft 38 of said motor being journaled in bearings 38^a—38^b and extending downward through the pumps so that the motor, and pumps have a common shaft. The motor may be geared to the shaft if desired but it is advantageous to operate the pumps with a single shaft.
- 15 A horizontally disposed frame 43 is secured to beams 3—4 and supports bearings 44—45.
- 20 A shaft 46 is journaled in bearings 44—45 and in worm gear housing 47 which is mounted on angle bar 48 supported by block 49 on cross beam 7. A worm gear 50 is rigidly mounted on shaft 46 and meshed with a worm 25 51 mounted on shaft 52 which is journaled in housing 47 and bearing 52^a. A yoke 53 is mounted on shaft 52 and carries a shaft 54 journaled in bearings 55—56. A bevel gear 57 is rigidly mounted on shaft 52 and meshed 30 with a bevel gear 58 rigidly mounted on shaft 54. A friction disc 59 is rigidly mounted on shaft 54. A spring 61 is hooked to a lug 62 on yoke 53 and connected to worm gear housing 47. A cable 63 is attached to lug 62 and passes over a sheave 64 to the boat. A 35 cable 65 is attached to lug 66 and passes under a sheave 67 to the boat.
- 40 A sheave 39 is mounted on an extension 40 on the upper end of sleeve 2 and a sheave 41, 45 on an extension 42 on the lower end of sleeve 2. A cable 69 is attached to extension 69^a and passes over sheave 39 to drum 70 on shaft 46. A cable 75 is attached to extension 71 and passes under sheave 41 to drum 70.
- 45 The lifting mechanism is thrown into gear by pulling cable 65 which swings yoke 53 downward thereby bringing disc 59 into engagement with friction wheel 60 as indicated by the dotted position 59^a in Fig. 14. The 50 action of friction wheel 60 upon disc 59 revolves it clock-wise and actuates shaft 54 carrying bevel gear 58. Bevel gear 58 actuates bevel gear 57 on shaft 52 and worm 51 actuates worm gear 50 on shaft 46 which carries drum 70. The drum 70 therefore revolves clockwise and winds up cable 75 and 55 unwinds cable 69. This action of the drum and cables lowers the slidably mounted frame until the proper depth is reached when cable 63 is 60 pulled and the disc 59 released from contact with friction wheel 60. The spring 61 now holds yoke 53 in the neutral position shown in Figs. 11, 12 and 13. The slidably mounted frame and sleeve are now swung fore and aft 65 of the boat by operating the cables 76 and 79.

These cables are operated by any suitable means such as motor actuated winding drums which are not shown for the reason that the actuating mechanism and drums are not claimed in this application. This swinging motion causes the ground engaging member A to plow back and forth in the river bed and the sand pump sucks the loosened sand through the grid 83 in the ground engaging member and into the sand channel 8, thence 75 through the intake 19 into the pump from thence it is forced out through outlets 20 and 21 into conduits 26 and 27. From the conduits 26 and 27 the sand travels through main conduit 28, flexible conduit 29 and conduit 80 30 into the riffle box 31. The sand runs over the riffle in the riffle box and the minerals are deposited in said riffle box. After recovering the gold or other mineral by this process, the sand may be conveyed to reservoirs for further treatment or may be returned to the river. The water pump takes water in at the intake 32 and discharges through outlets 33 and 34 into conduits 35 and 36 respectively. Conduits 35 and 36 convey the water 85 through inlets 11 and 13 to water channels 9 and 10 in the ground engaging member A from whence it is discharged through tapered discharges 12 and 14, respectively. The water discharges with considerable force and 90 dislodges sand and gravel from crevices which would otherwise not be disturbed by the action of the ground engaging member A. Since the upper ends of water channels 9 and 10 are open, water escapes through 95 ports 22 and 23 into the sand pump B and washes out the space between the impeller and the bottom of the pump so that sand will not accumulate and abrade the surfaces. The 100 grooves 81 in the impeller conform in contour to the impeller blades 82 and the centrifugal force, due to the whirling of the impeller, carries the water through grooves 81 to the periphery of the impeller.

To raise the slidably mounted frame, the 110 cable 63 is pulled which swings yoke 53 upward, bringing disc 59 into engagement with friction wheel 60 as indicated by the dotted position 59^b in Fig. 14. This reverses the 115 action described for lowering the frame. The drum 70 revolves anti-clockwise and winds up cable 69 attached to extension 69^a and unwinds cable 75, thereby elevating the 120 frame.

I claim:

1. In a hydraulic dredge, the combination with a boat provided with a frame carrying a horizontally disposed journal, of a vertically disposed open sleeve rotatably mounted on said journal; a frame slidably mounted in 125 said sleeve; a ground engaging member mounted on a lower end of said slidably mounted frame and a transversely disposed shaft, carrying a winding drum and a worm gear, journaled in said slidably 130

mounted frame; a yoke mounted on said horizontally disposed shaft; a bevel gear mounted on said horizontally disposed shaft; a shaft, carrying a friction disc on one end and a 5 bevel gear on the opposite end meshed with the bevel gear on said horizontally disposed shaft, journalled in said yoke; a friction wheel mounted on said actuating shaft and adapted to operate said friction disc, operating

10 cables for said yoke; an extension, carrying a sheave, on the upper end of said sleeve; a cable attached to the lower end of said slidably mounted frame and passing over said sheave to said winding drum; an extension, carrying 15 a sheave, on the lower end of said sleeve, and a cable attached to the upper end of said slidably mounted frame and running under said last named sheave to said drum.

2. In a hydraulic dredge, the combination 20 with a boat provided with a frame carrying a horizontally disposed journal, of a vertically disposed open sleeve rotatably mounted on said journal; a frame slidably mounted in said sleeve; a ground engaging member 25 mounted on the lower end of said slidably mounted frame, said ground engaging member being provided with a sand channel and two water channels, the water channels being open at the tops, each water channel being 30 provided with an intake at the side and a tapered discharge at the bottom and a horizontally disposed centrifugal sand pump mounted on said ground engaging member and provided with two outlets.

3. In a hydraulic dredge, the combination 35 with a boat provided with a frame carrying a horizontally disposed journal, of a vertically disposed open sleeve rotatably mounted on said journal; a frame slidably mounted in said sleeve; a ground engaging member 40 mounted on the lower end of said slidably mounted frame, said ground engaging member being provided with a sand channel and two water channels, the water channels being open at the tops, each water channel being 45 provided with an intake at the side and a tapered discharge at the bottom; a sand pump, having two sand outlets and two water intake ports, mounted on said ground engaging member so that said water intake ports are 50 in communication with said water channels in said ground engaging member and the sand intake of said pump is in communication with the sand channel of said ground engaging member; a vertically disposed main conduit mounted in said slidably mounted frame; a communicating conduit between 55 said main conduit and each of the sand outlets of said sand pump; a flexible conduit 60 in communication with said main conduit; a discharge conduit in communication with said flexible conduit and a riffle

box; a horizontally disposed water pump, mounted in said slidably frame above said sand pump and provided with two water outlets each in communication with one of the water channels in said ground engaging member and a common actuating shaft for said pumps; a motor mounted in said slidably mounted frame and connected to said actuating shaft.

4. In a hydraulic dredge, the combination 65 with a boat provided with a frame carrying a horizontally disposed journal, of a vertically disposed open sleeve rotatably mounted on said journal; a frame slidably mounted in said sleeve; a ground engaging member mounted on the lower end of said slidably mounted frame, said ground engaging member being provided with a sand channel and two water channels, the water channels being open at the tops, each water channel being 70 provided with an intake at the side and a tapered discharge at the bottom; a sand pump, having two sand outlets and two water intake ports, mounted on said ground engaging member being provided with a sand channel and two water channels, the water channels being open at the tops, each water channel being 75 provided with an intake at the side and a tapered discharge at the bottom; a sand pump, having two sand outlets and two water intake ports, mounted on said ground engaging member being provided with a sand channel and two water channels, the water channels being open at the tops, each water channel being 80 provided with an intake at the side and a tapered discharge at the bottom; a sand pump, having two sand outlets and two water intake ports, mounted on said ground engaging member so that said water intake ports are in communication with said water channels in said ground engaging member and the sand intake of said pump is in communication with the sand channel of said ground engaging member and a pair of removable linings, 24-25, mounted in said sand pump.

5. In a hydraulic dredge, the combination 85 with a boat provided with a frame carrying a horizontally disposed journal, of a vertically disposed open sleeve rotatably mounted on said journal; a frame slidably mounted in said sleeve; a ground engaging member 90 mounted on the lower end of said slidably mounted frame, said ground engaging member being provided with a sand channel and two water channels, the water channels being open at the tops, each water channel being provided with an intake at the side and a tapered discharge at the bottom; a sand pump, having two sand outlets and two water intake ports, mounted on said ground engaging member so that said water intake ports are 95 in communication with said water channels in said ground engaging member and the sand intake of said pump is in communication with the sand channel of said ground engaging member; a pair of removable linings, 100 24-25, mounted in said sand pump; a horizontally disposed water pump, mounted in said slidably frame above said sand pump and provided with two water outlets each in communication with one of the water channels in said ground engaging member and a common actuating shaft for said pumps; a motor mounted in said slidably mounted frame and connected to said actuating shaft.

LEROY VORHIES.
